UNITED STATES PATENT OFFICE.

JOHN T. FOSTER, OF WILMINGTON, DELAWARE, ASSIGNOR TO H. W. BUTTERWORTH & SONS COMPANY, A CORPORATION OF PENNSYLVANIA.

CLOTH-CLAMP.

1,159,755.

Specification of Letters Patent.

Patented Nov. 9, 1915.

Application filed May 26, 1915. Serial No. 30,687.

To all whom it may concern:

Be it known that I, JOHN T. FOSTER, a citizen of the United States, and resident of Wilmington, county of New Castle, and State of Delaware, have invented an Improvement in Cloth-Clamps, of which the following is a specification.

In automatic cloth clamps as commonly employed in tentering and other machines for grasping the selvages when stretching or otherwise treating cloth, and especially in those characters of clamps in which an automatic tripping device is used for insuring the proper gripping of the cloth, there is a tendency to soil the cloth by grease from the tripping device being wiped upon the cloth by the sliding of the latter under the tripping device in setting the clamp, the grease or oil referred to being received upon the tripping device from the oiled hinges of the chain links which carry the clamps.

The object of my invention therefore, is to provide a construction of automatic cloth clamp in which the tripping device is so shielded and guarded against receiving grease from the chain links that the normal operation of the device may be performed without danger of injury to the cloth.

With the above and other objects in view, the nature of which will be more fully understood from the description hereinafter, the invention consists in the novel construction of cloth clamp as hereinafter more fully described and defined in the claims.

Referring to the drawings: Figure 1 is a front elevation of a cloth clamp and a portion of the chain embodying my invention; Fig. 2 is a transverse sectional view of the same taken on line $x-x$ of Fig. 1; Fig. 3 is an inverted plan view of the clamp plate and shield of the clamp; and Fig. 4 is a perspective view illustrating the clamp plate and shield before being assembled into a unitary structure. Fig. 5 is a view in section of a modified form of the shield with integral extensions.

2, 2 represent links of a chain and are jointed together by means of hinge pins 3 of any suitable construction. The joints of these hinges are usually oiled or greased, as will be understood. A portion of the links along the length of the chain (preferably every other link) may be provided with a suitable cloth clamping mechanism as illustrated. As shown, the upper part of the link

is formed with a bed 4 upon which is suitably secured the clamping plate 6 forming one of the jaws of the clamp. The clamping plate 6 may be made with a flange at one side fitting over the edge of the bed and also provided with downwardly extending tapered pins or lugs 8 which fit into corresponding holes in the bed to properly position and hold the plate in proper relation with the bed. The bed is formed with an aperture 5 and the plate 6 is provided with a downwardly extending shield portion 9 which extends into the slotted portion 5 of the bed, as will be clearly understood from the drawing. In the preferred form of the construction, the shield is made of pressed sheet metal of the general shape illustrated in Figs. 2 and 4 to form a semi-cylindrical chamber. This shield portion 9 is adjusted in the aperture 7 in the clamping plate 6, and is soldered or brazed therein at 10 so that it becomes a unitary part of the plate. The shield forms a pocket extending below the upper surface of the plate and shields the cloth and the tripping device 15 against receiving grease or oil which may work along the chain from the journals thereof. The upper part of the bed is provided with an overhanging arm 11 upon which is pivoted the movable clamping jaw 12 having the clamping edge 13 for gripping the cloth. This pivoted jaw 12 is provided with a rearward lug 14 in which is pivoted at 16 the automatic tripping finger or dog 15. As shown in Fig. 2, this dog 90 has the contacting finger 15 directed toward the clamping edge 13 of the jaw and between it and the hinge 16, and also has a rearward portion 17 which acts as a counterweight and also a fulcrum for the tripping finger in the normal operation of the apparatus.

18 is a projection or stop to limit the amount of movement to the tripping finger when released from the cloth.

In the operation of the clamp, the cloth 19 rests over the clamping plate 6 and thereby extends over the pocket of the shield 9. The tripping finger 15 rests upon the cloth immediately above the pocket, and the rear 105 or fulcrum end 17 of the tripping finger is sustained against downward motion by the clamping plate at the rear of the pocket. When the parts are in the position indicated in Fig. 2, the clamping edge 13 of the 110

jaw 12 is held clear of the cloth. As the cloth is drawn from under the tripping finger, the end 15 drops down to the dotted position, and this releases and pulls down 5 the jaw 12 so that it assumes the clamping position indicated in dotted lines, to clamp the selvage near the edge of the cloth. Where there is no shield 9, the tripping finger 15 extends down through the aperture 10 5 of the bed of the clamp, and is in position to come in contact with grease or oil either dropping or working along the surface of the chain. It will be understood that as these chains pass about guide rollers at each 15 end, there are various positions assumed which are liable to cause the oil or grease to become extended over the surface of the chains and ultimately reach the tripping finger. As the chains come around into a 20 position to grip the cloth, the clamp 12 has its lower part thrown backward to lift the finger clear of the entering cloth, after which the clamp is allowed to assume the position shown in Fig. 2 and with the tripping finger 15 resting upon the surface of 25 the cloth, and thereby be sustained and caused to operate to hold the gripping jaw 12 out of gripping position. If there is any grease upon this tripping finger, it is manifest that the same will be wiped upon the 30 surface of the delicate fabric, if said tripping finger were not guarded against contact with the grease. It will be understood that by providing the shield or pocket 9 in 35 the clamping plate 6 so as to act as a shield for the tripping finger against the grease of the chain proper, the said tripping finger remains clean and no injury to the cloth arises. I have shown the construction of 40 shield or pocket in the form I prefer to make it, as the pressed sheet metal enables accuracy and lightness to be secured, and also obviates the necessity of costly finishing of the interior surface. The union of the 45 edges of the shield to the boundaries of the slot 7 by means of solder completely shuts off the possibility of the passage of grease between the union of the plate and the shield.

50 While I have shown the preferred construction in which the plate may be cast and the shield formed of pressed metal, it will be understood that I may form the entire structure of a casting or pressed metal 55 and of integral form, if so desired, and I therefore do not limit myself to the minor details here shown. The plate 6 is usually made of brass, while the chain and bed are made of cast iron, but I do not restrict myself to the necessity of employing a different

metal in the application of my invention to a cloth clamp, as the entire structure may be formed of one casting. It will also be understood that while I have shown a particular form of cloth clamp in which the 65 gripping jaw is sustained by the tripping finger controlled by the cloth, the general construction of this clamp may be greatly varied both as to the construction of the jaw and the tripping finger, provided the 70 same general principle of operation remains, and it is therefore to be understood that the particular details of the tripping finger and the jaw which it controls are illustrated as an example of an automatic cloth clamp 75 structure to which my improvements may be applied, and therefore the details of the clamp structure itself may be greatly modified without departing from the spirit of the invention.

Having now described my invention, what I claim as new and desire to secure by Letters Patent, is:—

1. In a cloth clamp, the combination of a chain link portion having a clamping plate 85 portion having its upper surface formed with an aperture and said aperture closed at the bottom by a shield or protecting pocket, with a cloth clamping jaw, and a tripping device for controlling the time of 90 operation of the jaw, said tripping device initially sustained by the cloth and positioned above the pocket whereby it may enter the pocket and be shielded thereby from the grease of the chain structure when 95 the jaw clamps the cloth.

2. In a cloth clamp, a chain link structure having a bed formed with an aperture through the same, combined with a clamping plate fitting the bed and having a pocket 100 opening through its upper surface said pocket having its bottom and sides extended through the aperture in the bed and constituting a shield to prevent passage of grease from the chain link, a clamping jaw for 105 clamping the cloth, and a pivoted tripping finger hinged to the clamping jaw and initially resting upon the cloth to hold the jaw out of clamping position, said tripping finger arranged above the pocket and adapted 110 to enter therein and be shielded by the bottom and sides of the pocket against contact with the grease of the chain link structure.

In testimony of which invention, I here- 115 unto set my hand.

JNO. FOSTER.
